UNITED STATES PATENT OFFICE

2,084,910

ELECTRIC SWITCH GEAR

Charles H. Hill, Drexel Hill, Pa., assignor to General Electric Company, a corporation of New York

Application January 8, 1936, Serial No. 58,029

5 Claims. (Cl. 173—332)

My invention relates to electric switch gear, more particularly to switch contact structure, such as disconnect contact structure, for electric switch gear of the drawout type.

5 In electric switch gear of the drawout type for example, wherein a circuit breaker unit is bodily movable to connected and disconnected positions with respect to stationary busbar structure, it is generally customary accurately to align the 10 circuit breaker unit with respect to the coacting stationary portions of the circuit so that the coacting disconnect contacts engage within a very limited range of misalignment. Where plug and socket disconnect contact structure is used, as 15 is often the case, it will be apparent that the switch gear must be quite accurately aligned and that this requires very careful machining and fabrication of the structure, resulting in appreciably higher cost. The problem of alignment is 20 further complicated by the fact that in switch gear of the aforesaid type the disconnect contact structure must have a comparatively high normal current carrying capacity. Accordingly, it is highly desirable that the disconnect contacts 25 maintain positive low resistance contact, notwithstanding appreciable misalignment of the coacting movable and stationary elements.

A principal object of my invention is the provision of improved relatively movable contact structure which is effective to maintain comparatively high current carrying capacity notwithstanding appreciable misalignment of the relatively movable contact elements, and which is 30 efficient in operation and simple, rugged and inexpensive in construction.

35 In accordance with my invention in one embodiment thereof, both of the relatively movable elements are provided with contact surfaces, preferably plane, which are interconnected in the closed circuit position by a pair of contact members arranged in a scissors-like manner with respect to each other and mounted with respect to one of said elements. By reason of the flexibility and automatic adjustment to forces either 40 in a generally transverse or longitudinal direction inherent in a scissors-like arrangement, accurate alignment, either lateral or angular, of the relatively movable switch gear elements is 45 unnecessary within the limits of the contact area. The disconnect switch overtravel or "wipe", as 50 well as the desired contact pressure, may be suitably provided for by resilient means, such as springs, interconnecting and biasing the contact members for scissors-like operation.

55 My invention will be more fully set forth in the following description referring to the accompanying drawing, and the features of novelty which characterize my invention will be pointed out with particularity in the claims annexed to 60 and forming a part of this specification.

Referring to the drawing, Fig. 1 is an elevational view of relatively movable portions of electric switch-gear of the drawout type having disconnect contact structure embodying the present invention: Fig. 2 is an enlarged elevational view, partly in section, of the coacting disconnect contacts, and Fig. 3 is a plan view of the contacts shown by Fig. 2.

The drawout type switch gear shown by Fig. 1 comprises a stationary structure 1 housing the stationary circuit connections, such as busbars (not shown), and a relatively movable switch gear unit 2 including a circuit breaker 3. The terminals 3' of the circuit breaker are electrically connected to disconnect contacts, but one of which is shown at 4, for connecting the circuit breaker through coacting stationary disconnect contacts 5 to the busbar circuits. As illustrated, the switch gear is in the open circuit or isolated position, and to connect the circuit breaker to the busbars, the unit 2 is rolled towards the housing 1 so that the contacts 4 and 5 are in engagement. This general type of switch gear being well known, further description thereof is believed unnecessary for a thorough understanding of the present invention.

Referring more particularly to Figs. 2 and 3 which illustrate in greater detail the disconnect switch contact structures 4 and 5, the relatively movable elements include insulating conductor bushings 6 and 7 for circuit terminating in contact plates 8 and 9 having opposing plane contact faces 8' and 9'. Suitably mounted with respect to one of the aforesaid elements, in the particular instance the stationary element, are a pair of contact members 10 and 11 co-pivotedly mounted at 12 on a bracket support 13 which is mounted, as at 14, on the conducting plate 9. The contact members 10 and 11, which are generally of S-shape, are arranged in a scissors-like manner with respect to each other and are suitably resiliently biased, such as by tension springs 15 and 16, in scissors closing movement, that is, so that one end of the member 10 and one end of member 11 are at all times biased into contact engagement with the contact surface 9'. The opposite ends of the springs 15 and 16 are anchored, such as by through-pins 15' and 16' respectively, within depressions in the ends of the contact members.

The movable contact element may comprise simply the contact plate 8 arranged to move into direct butt engagement with the corresponding ends of the members 10 and 11. The pivot pin 12 interconnecting the contact members forms the scissors fulcrum and is movable for limited transverse movement within the slot 12' formed in the bracket 13. With this arrangement, relative closing movement of the contact plates 8 and 9 within predetermined limits results simply

in scissors opening movement of the members 10 and 11, thereby tensioning the springs 15 and 16, and biasing the contact ends into engagement with the plane contact surfaces 8' and 9', respectively. The scissors pivot or fulcrum at 12, as above pointed out, has a limited transverse movement within the slot 12'.

For the purpose of providing improved contact engagement between the members 10 and 11 and the coacting contact plates 8 and 9, the contact ends of the aforesaid scissors-like structure are formed as cylinders, or the equivalent thereof, at 17 and 18, respectively, so as to make substantially line contact engagement with the coacting plane surfaces. That is, the contact is concentrated at a point of very high unit contact pressure. The contact engagement is further improved by providing the coacting contact surfaces at 19 and 20 with inserts or plating of good contact material, such as silver for example. The coacting contact surfaces at the plates 8 and 9 are shown as of appreciable area, in order to compensate for a considerable degree of misalignment and to provide for the scissors-like wiping movement during the contact making and breaking operation. This also insures self-cleaning of the coacting contact surfaces.

It will be apparent from the above description that notwithstanding misalignment of the contact plates 8 and 9, either in a transverse or angular sense, the members 10 and 11, by reason of the tension springs 15 and 16, automatically adjust themselves to the coacting plane contact surfaces 8' and 9', respectively, so that high current carrying capacity is maintained.

The contact structure, while shown as including a definite scissors pivot or fulcrum, is obviously not limited to this particular arrangement, and it should be understood that by the term "scissors-like" as used herein, I intend to comprehend relatively movable members arranged generally in scissors or X fashion.

It should furthermore be understood that my invention is not limited to specific details of construction and arrangement thereof herein illustrated, and that changes and modifications may occur to one skilled in the art without departing from the spirit of my invention.

What I claim as new and desire to secure by Letters Patent in the United States is:

1. Electric switch contact structure comprising a pair of relatively movable elements, said elements provided with contact surfaces, a pair of contact members mounted with respect to each other in a scissors-like manner, means for mounting said contact members with respect to one of said elements, said contact members arranged to interconnect said elements so that in the closed circuit position of said contact structure the opposite ends of each member engage respectively the contact surfaces of said relatively movable elements, and means for biasing said contact members into contact engagement with said elements.

2. Electric switch contact structure comprising a pair of relatively movable elements, each element provided with a substantially plane contact surface, a pair of contact members mounted with respect to each other in a scissors-like manner arranged to interconnect said elements so that in the closed circuit position the opposite ends of each contact member engage respectively the

plane contact surfaces of said relatively movable elements, means for mounting said contact members with respect to one of said elements, and means resiliently biasing the aforesaid scissors-like contact arrangement so as to oppose scissors movement of said members after engagement of said contact structure.

3. Electric switch contact structure comprising a pair of relatively movable elements, each of said elements provided with a substantially plane contact surface of appreciable area, a pair of contact members arranged in scissors-like manner between said contact surfaces, means mounting said scissors-like arrangement for limited movement with respect to one of said elements, and means resiliently biasing said scissors-like arrangement so as to increase the contact pressure between said scissors-like arrangement and said plane contact surfaces respectively and for automatically positioning said scissors-like arrangement with respect to said plane contact surfaces respectively for maintaining good contact relation therebetween.

4. Electric switch contact structure comprising a pair of relatively movable elements, each of said elements having a contact surface, a pair of contact members arranged in scissors-like manner and pivotally mounted with respect to one of said elements, said scissors-like arrangement interconnecting said contact surfaces in the closed circuit position and arranged so that the opposite ends of each contact member engage respectively the contact surfaces of said relatively movable elements, said contact members having cylindrical shaped contact portions at the contact ends thereof for engaging in substantially line contact the coacting contact surfaces, and means resiliently biasing said members for scissors movement so that a contact portion of each of said contact members engages the contact surface of said one of said elements, the contact surface of the other of said elements engaging in the closed circuit position the contact portions at the other ends of said contact members, the contact surfaces of said elements being in good contact relation notwithstanding lateral or angular misalignment of said elements.

5. Electric switch contact structure comprising a pair of relatively movable elements, each of said elements having a contact surface of appreciable area, a pair of contact members arranged in scissors-like manner for interconnecting said contact surfaces in the closed circuit position, a pivot pin interconnecting said contact members forming the scissors fulcrum therefor, bracket structure mounted on one of said elements for supporting said scissors-like arrangement, said bracket structure having a slot within which said pivot pin is positioned for allowing bodily transverse movement of said scissors-like arrangement, and spring means interconnecting the ends of said contact members for biasing said ends into contact engagement with the contact surfaces respectively of said elements, scissors-like movement of said contact members in accordance with closing movement of said elements flexing said spring means so that said elements are interconnected in good contact relation notwithstanding limited transverse and angular misalignment thereof.

CHARLES H. HILL.
